UNITED STATES PATENT OFFICE

GEORGE W. BORTON, OF NEW LISBON, NEW JERSEY, ASSIGNOR TO PENNSYLVANIA CRUSHER COMPANY, OF NEW YORK, N. Y., A CORPORATION OF NEW YORK

COAL BREAKER

Application filed November 24, 1930. Serial No. 497,861.

My invention relates to apparatus for breaking coal, more particularly structures of the type familiarly known as Bradford breakers, instances of which are found in the Borton and Hiller Patent, No. 1,086,129, dated Feb. 3, 1914, and in the Hiller Patent, No. 1,322,568, dated Nov. 25, 1919.

The material to be broken or reduced in breaker structures of this type is familiarly known as run-of-mine coal which includes the fines of such material broken during the loading operation and/or in transit and lumps of varying size. Run-of-mine coal includes foreign material in the shape of sulfur balls, pieces of slate and, to a greater or less degree, pieces of iron in the shape of bolts, spikes and other fragments commonly met with in railroad practice which of course cannot be broken and such foreign material feeds forward with the coal that is being reduced in size. It is desirable to collect this foreign material for periodic discharge, preferably in a space within the drum that is clear of the lifting shelves usually employed in these structures, and I provide such space by disposing a diaphragm at the end of the cylinder or drum opposite the feed end and a short distance from a wall which closes such end.

One object of my present invention therefore is to provide means whereby such foreign material and/or tramp iron may be trapped and collected at a suitable point within the drum or cylinder.

A further object of my invention is to provide means for collecting such foreign material and/or tramp iron at the end of the cylinder opposite the feed end.

And a still further object of my invention is to provide a supplemental wall within the crushing chamber of the breaker structure at the end of the cylinder opposite the feed end; such supplemental wall being substantially circular in contour; slightly less in diameter than the internal diameter of the crushing chamber, and spaced a suitable distance from the end wall.

In addition this plate or wall is preferably recessed at its edge so as to provide an opening for the passage of tramp iron and/or

other foreign material which may be diverted by a suitable plow and trapped in the space between the supplemental plate and the end of the crushing chamber. In some instances I may provide the supplemental wall with a central opening. Such supplemental wall may be in one piece or section, or it may be built up of a plurality of sections; either form being within the scope of my invention.

These and other features of my invention are more fully described hereinafter; reference being had to the accompanying drawings, in which:

Figure 1 is a longitudinal section of a breaker structure within the scope of my invention, having a supplemental wall at one end of the crushing chamber.

Figs. 2 and 3 are end elevations, Fig. 2 showing a part of the cylinder in section, illustrating forms of supplemental walls which I may employ, and

Figs. 4 and 5 are views illustrating forms of plows which may be employed with the supplemental wall.

Coal breakers of the type to which my present improvements have been applied comprise in general a cylinder or drum made up of a suitable frame and a foraminous wall; the whole being mounted for rotation. In the present instance I have shown a wall made up of sections or sets of apertured plates set circumferentially, which plates may be provided with edge flanges disposed in lapped relation and assembled to form the cylinder of the breaker structure. It will be understood of course that while such plates are preferred, I do not wish to be limited to the use of plates of the type illustrated in the construction of the breaker drums or cylinders with which the improvements forming the subject of my present invention may be employed.

As illustrated in the accompanying drawings, the cylinder may comprise a frame or spider 1 at one end, a closed frame or wall 2 at the opposite end, and longitudinal members in the form of I-beams 3, which may be of rail type if desired, connecting these parts. Arranged internally of the beams 3 and con-

fined thereto by suitable bolts are sets of foraminous plates 4 which make up what may be termed the screen portion of the breaker drum or cylinder; said plates being 5 preferably lapped at their points of engagement and bolted or otherwise secured to each other or to said beams.

The drums or cylinders of structures of this type are usually provided with lifting 10 shelves as indicated at 5, and such shelves may extend substantially the full length of the same; being either of sectional construction or continuous members. In practice these shelves are preferably disposed opposite 15 certain of the beams extending longitudinally of the drum or cylinder and they may be secured to said beams by the fastening means employed for holding the plates thereto, or in any other suitable manner. The 20 inner surfaces of the cylinder wall may be provided with deflectors 6, which may be of the type illustrated in the patent of Plimpton, No. 1,700,687; such deflectors being set at a suitable angle so that the material fed 25 into one end of the cylinder, in the present instance at the left end of the same, may be moved toward the opposite end of the cylinder as the latter rotates; in the present instance such material moving toward the 30 right.

Coal breakers of this type are usually mounted upon trunnions, and these are indicated at 7 and 8 in Fig. 1; one trunnion being carried by the frame or spider 1 while 35 the other is carried by the wall 2 at the opposite end of the cylinder. These trunnions may be supported by suitable bearings 9 and 10 in which they are rotatably mounted.

In carrying out my present invention I 40 propose to locate a supplemental wall or diaphragm within the crushing chamber adjacent to the closed end 2 of the same.

Such supplemental wall or diaphragm may be in the form of a circular plate 12, mounted 45 on stud bolts 13, or otherwise, and disposed about twelve inches from the closed end wall 2 and parallel therewith. This end plate or diaphragm 12 should be spaced a slight distance from the screen plates 4, as indicated 50 at α , and the extent of such spacing depends upon the character of the discharge apertures formed in the screen plates. The edge of the plate or diaphragm 12 is preferably notched or recessed as indicated at 14; the size of 55 such opening being approximately fourteen by twenty inches, more or less, to permit a discharge plow 15, which may be mounted in the position illustrated in Figs. 2 and 4, to feed tramp iron and/or the like into the 60 compartment or space between said plate or diaphragm 12 and the end wall 2 of the cylinder or drum. This plow may be an independent member secured to the plate 12 and the wall of the cylinder in the manner indicated, or in some instances I may employ part

of the plate removed to form the opening 14 as an integral plow, as indicated at 15^a, Figs. 3 and 5. The plate 12 forming the supplemental wall or diaphragm may be continuous, as illustrated in Fig. 2, or it may be provided with an opening 12^a, centrally disposed, as illustrated in Fig. 3. Such opening would permit an overflow of the material trapped behind the plate 12 in case the space became clogged. 70

In action, any tramp iron or other foreign material carried through the breaking chamber from the feed end of the cylinder will be finally caught by the plow and diverted into the compartment or space between said plate 12 and the end wall 2. It will be obvious of course that coal and foreign material, refuse and the like, will also be caught by the plow and diverted into the space behind the plate 12 with the tramp iron. This space is preferably free of the lifting shelves 5 and all of this trapped material will ride with the motion of the breaker cylinder to a certain extent; constantly sliding back but not violently dumping in the manner in which material subjected to the regular lifting shelf action drops. Any broken coal not discharged through the central aperture 12^a of the plate 12 (if such form of plate is used) and not moved back into the main breaking chamber through the circumferential space between such plate 12 and the perforated wall of the cylinder, will be discharged through such perforated wall. If it is desirable to make the surface of this space relatively smooth, the heads of the bolts securing the screen plates to the longitudinal members may be flush with said plates. 95

The provision of the plate 12 forming a supplemental wall or diaphragm spaced from the closed end wall 2 of the breaker chamber will definitely entrap tramp iron, and any coal entrained therewith will be broken down and either discharged through the apertures in the screen plates 4 or escape under said plate 12 to the main chamber. Additionally, the presence of the tramp iron will break down any friable refuse present which can not stand the gradual tumbling process and permit discharge through the screen plates. My improved construction avoids all danger of damage to the breaker structure which might arise from the tumbling of entrained iron in a breaker structure having a closed end. 100

Periodically, depending upon the amount of tramp iron and/or other foreign material collecting, the operator will have to empty the space between the plate 12 and the end wall 2. This may be done by providing a hinged connection for one or more of the screen plates forming the circumferential wall of the space between the supplemental wall or diaphragm 12 and the end wall 2 of the breaker structure, or through an opening 16 which 115

may be provided in said end wall 2; such opening being normally closed by a door 2^a.

I claim:

1. The combination with a coal breaker comprising a cylinder made up of a framework mounted for rotation and perforated plates forming a circumferential wall carried thereby; said cylinder being open at one end and having a wall closing its opposite end, of a supplemental wall or diaphragm disposed within said cylinder and spaced a short distance from the closed end of the same; said supplemental diaphragm being carried by the end closing wall and circumferentially spaced from the perforated plates forming the cylindrical wall of the coal breaker.

2. The combination, in a coal breaker, of a cylinder made up of a frame-work mounted for rotation and a wall of perforated plates; said cylinder being open at one end and having a wall closing its opposite end, and a supplemental wall or diaphragm disposed within said cylinder and spaced a short distance from the closed end of the same; said supplemental diaphragm being carried by the end closing wall and circumferentially spaced from the perforated plates forming the cylindrical wall of the coal breaker.

3. The combination with a coal breaker comprising a rotatable cylinder made up of a frame-work and a series of perforated plates connected thereto and forming the circumferential wall; said cylinder being open at one end and having a wall closing its opposite end, and a circular plate having a central opening and spaced a short distance from the closed end of the cylinder; said circular plate being carried by the end closing wall and circumferentially spaced from the perforated plates forming the cylindrical wall of the coal breaker.

4. The combination, in a coal breaker, of a rotatable cylinder made up of a frame-work and a series of perforated plates connected thereto and forming the circumferential wall; said cylinder being open at one end and having a wall closing its opposite end, and a circular plate having a central opening secured to said structure and spaced a short distance from the closed end of the cylinder; said circular plate being carried by the end closing wall and circumferentially spaced from the perforated plates forming the cylindrical wall of the coal breaker.

5. In a coal breaker, the combination with a rotatable cylinder comprising a suitable frame including longitudinal members and perforated plates secured thereto and forming the circumferential wall of said cylinder; the latter having a feed opening at one end and a closed wall at its opposite end, of a circular plate located within said cylinder and spaced a short distance from the closed end of the same; said plate being carried by said closed end out of contact with the perfo-

rated plates making up the wall of the cylinder and the space defined by said plate being free from lifting and deflecting means.

6. In a coal breaker, the combination with a rotatable cylinder comprising a suitable frame including longitudinal members and perforated plates secured thereto and forming the circumferential wall of said cylinder; the latter having a feed opening at one end and a closed wall at its opposite end, of a circular plate located within said cylinder and spaced a short distance from the closed end of the same; said plate being notched at its outer edge and the space defined thereby being free from lifting and deflecting means, and a plow associated with said plate adjacent such notch.

7. In a coal breaker, the combination with a rotatable cylinder comprising a suitable frame including longitudinal members and perforated plates secured thereto and forming the circumferential wall of said cylinder; said cylinder having a feed opening at one end and a closed wall at its opposite end, of a circular plate disposed within said cylinder; said plate being spaced a short distance from the closed end of the same and positioned to provide an annular space between its marginal edge and the perforated plates forming the wall of said cylinder; the end space defined by said circular plate being free from lifting and deflecting means.

8. In a coal breaker, the combination with a rotatable cylinder comprising a suitable frame including longitudinal members and perforated plates secured thereto and forming the circumferential wall of said cylinder; said cylinder having a feed opening at one end and a closed wall at its opposite end, of a circular plate disposed within said cylinder; said plate being disposed a short distance from the closed end of the same and having its marginal edge notched or recessed and circumferentially spaced from the perforated plates forming the wall of said cylinder and the space between said circular plate and the closed wall of the cylinder being free from lifting and deflecting means, and a plow arranged to divert material through said notched portion of said plate.

9. In a coal breaker, the combination of a rotatable cylinder comprising a suitable frame including longitudinal members and perforated plates secured thereto and forming the circumferential wall of said cylinder; said cylinder having a feed opening at one end and a closed wall at its opposite end, and a circular plate disposed within said cylinder and spaced a short distance from the closed end of the same; said plate forming a space free from lifting and deflecting means for the collection of tramp iron and the like and being notched at its edge to permit the passage of such tramp iron into the space defined by such plate.

10. In a coal breaker, the combination of a rotatable cylinder comprising a suitable frame including longitudinal members and perforated plates secured thereto and forming the circumferential wall of said cylinder; said cylinder having a feed opening at one end and a closed wall at its opposite end, a circular plate disposed within said cylinder and spaced a short distance from the closed 5 end of the same; said plate forming a space for the collection of tramp iron and the like and being notched at its edge to permit the passage of such tramp iron into the space defined by such plate, and a plow associated 10 with such plate to divert material into the space defined thereby.
